UNITED STATES PATENT OFFICE.

WILLIS JOHN PIPPERT, OF RIDLONVILLE, MAINE.

UNDERLAY FOR PRINTING ON PAPER BAGS AND THE LIKE AND THE PROCESS OF MAKING SAME.

Application filed April 17, 1920. Serial No. 374,670.

To all whom it may concern:

Be it known that I, WILLIS J. PIPPERT, a citizen of the German Republic, residing at Ridlonville, in the county of Oxford, State 5 of Maine, have invented certain new and useful Improvements in Underlays for Printing on Paper Bags and the like and the Processes of Making Same, of which the following is a description.

10 The invention relates to underlays used in printing upon paper bags, cartons, or the like, which when folded and lying flat, have a plurality of thicknesses. The purpose of this invention is to form a matrix whereon 15 the bags are to be placed during printing, and which supports the bag at all points, and exposes to the printing mechanism a substantially flat surface support so that the impressions shall be even and equally distinct 20 throughout.

In the drawing, Fig. 1, is a view of that surface of a bag, upon which printing is to be done. Fig. 2 is an edge view from the side of a bag. Fig. 3 is a view of the bag on 25 the reverse side, this being a part of the bag which requires support. Fig. 4 shows a bag lying on material from which the matrix is to be formed. Fig. 5 is a longitudinal section on line 5—5 of Fig. 4. Fig. 6 is a plan 30 view of the completed matrix. Fig. 7 is an enlarged longitudinal section of the matrix on the line 7—7 of Fig. 6. Fig. 8 is an enlarged cross section on the line 8—8 of Fig. 6 with the bag shown thereon. Fig. 9 is an 35 enlarged cross section on the line 9—9 of Fig. 6 with the bag shown thereon.

The invention is adapted for use with any object having varying thicknesses and upon which it is desired to print or impress 40 characters. To describe the process of making the underlay and to show its use, it has been illustrated and described in connection with a paper bag of the bellows type having a lining therein but may be used with any article of uneven thickness upon which it is 45 desirous of printing.

The paper bag 1 of the bellows type when folded in the usual manner is made up of 50 thicknesses varying from 2 to 21 plies of paper as is well understood in paper bag making. At the bellows position 2 thereof there are 8 thicknesses of paper; at both seams 3 there are nine thicknesses; between the seams 3 at 4 five thicknesses; at 5 55 six thicknesses; and the portions 6, 7, 8 and

9 have respectively sixteen, fourteen, nineteen and fifteen thicknesses. The variance in the thicknesses is due to the manner in which the bag is folded when manufactured. The bag, when further folded and made flat 60 for the purpose of printing thereon the usual trade marks, decorations and dealers' names, has its thicknesses considerably multiplied. The bottom and part of the lower end of the bag as shown in Fig. 3, is usually folded 65 along the line 10.

The matrix 11 is made from the sheet 12 of unvulcanized rubber, about one-sixteenth of an inch in thickness which has been previously compounded so that it may ultimately be vulcanized. Beneath the sheet 12 a thin sheet of tissue paper 13 is placed and a second sheet of tissue, 14, is placed over the sheet 12. The tissue sheets are used so that the rubber sheet shall not stick to the 75 materials used with it in shaping or forming the matrix. A bag 1 of the kind to be printed upon, is placed over the rubber sheet 12 and on top of the tissue sheet 14, with the reverse side (that is the side opposite the 80 side which is ultimately to be printed upon) next to the tissue as shown in Fig. 4. The assembled parts are then placed in a steam heated press and pressure applied to them until the bag 1 has been pressed into the rubber sheet 12 so that it takes the exact outline and shape of the reverse side of the bag. The press is preferably heated before the assembled parts are placed therein. The assembled parts are subjected to heat for about 85 five minutes, in which time the rubber sheet is vulcanized. It is, however, not necessary to press the bag 1 into the rubber sheet 12 until their upper surfaces are flush. It is just as expedient if the bag is pressed into 90 the rubber sheet 12 so that it is not quite flush with the upper surface of the rubber sheet, so that in the subsequent use of the finished matrix, during printing, the printing type or plate shall come in contact only 95 with the bag and not with the matrix. After vulcanization is complete the bag is lifted from the rubber sheet 12 and the tissue sheets 13 and 14 removed. The matrix 11 is complete and has impressed upon its surface the exact configuration of the reverse 100 side of the bag. The greater thicknesses of paper are deeper in the finished matrix than the lesser thicknesses. Thus the part 6 of the bag which is 16 ply is substantially again 105 110

as deep as the part 2 which is 8 ply. All the varying thicknesses of the bag are proportionately deeper according to their varying relative thicknesses. The matrix 11 is then placed in a proper printing press and is ready to act as an underlay for printing on paper bags of the same construction as the bag used in forming the matrix. The bag is placed upon the matrix with the corresponding parts of the matrix and bag together, the upper surface of the bag, upon which the printing is to be done, is substantially flat and even and the impression taken from the type or plate will be the same throughout without ghost-lines or imperfect impressions. The matrix forms a firm bed for printing upon and avoids the great inconveniences heretofore experienced in printing upon paper objects of uneven thicknesses.

Each different type of bag or other article to be printed upon will require a matrix of its own type.

I claim:

1. The process of making an underlay for use in printing upon like articles of varying thickness, the steps which consist in placing upon a sheet of substantially flat impressionable material one of the articles to be printed upon, applying pressure to the article and the impressionable sheet until the shape and the varying thicknesses of the article are impressed into said sheet and finally permanentizing the sheet so as to retain the impressed shape and varying thicknesses of the article therein, the said impression having a contour shaped to compensate for the uneven thickness of the article and to successively receive said articles in a manner to present exposed surface thereof in an even condition for receiving printing thereon.

2. The process of making an underlay for use in printing upon articles of uneven thickness, which consists in placing upon an impressionable material one of the articles to be printed upon, applying pressure to said article to produce an impression thereof in said material, said impression having a contour adapted to compensate for the uneven thickness of the article and to successively receive said articles in a manner to present the exposed surface thereof in an even condition for printing.

3. The process of making an underlay for use in printing upon articles of uneven thickness, which consists in placing upon a sheet of unvulcanized rubber one of the articles to be printed upon, applying pressure

to said article in the presence of heat to produce an impression thereof in said sheet of rubber and to thereby form a recess therein having a bottom contour adapted to compensate for the uneven thickness of the article and to successively receive articles in a manner to present the exposed surface thereof in an even condition for printing and retaining the combined article and sheet of rubber in the presence of heat until the latter is vulcanized.

4. The process of making an underlay for use in printing upon paper bags of the bellows type in a folded condition of varying thicknesses, which consists in placing upon a sheet of unvulcanized rubber one of said bags in a folded condition, applying pressure to said bag to produce an impression thereof in said sheet of rubber and to thereby form a recess therein having a bottom contour adapted to compensate for the varying thickness of said bag and to receive successive bags in a manner to prevent the exposed surface thereof in an even condition for printing and then vulcanizing the sheet to fix the impression therein.

5. An underlay for use in printing upon like articles of varying thickness comprising a sheet of underlay material provided with an impressed recess formed in the substance of the underlay material and depressed in relation to the normal surface of the underlay material, said recess being a substantially permanent impressed facsimile of one of said articles in the underlay material, said material being capable thereafter of supporting other specimens of said articles in the said recess in such a manner so as to present a substantially flat surface for receiving printing impressions.

6. An underlay for use in printing upon paper bags of varying thicknesses, or like articles, comprising a sheet of yieldable vulcanized rubber, having depressions formed therein corresponding to the varying thicknesses of the article to be printed upon, the varying depths of the depressions being substantially equal to the thicknesses of the corresponding portions of the article, the depressions constituting a recess for the reception of the article to be printed upon and the outer edges of the depressions constituting a guide for positioning the article, and whereby the article to be printed upon presents an exposed surface in an even condition for receiving printing impressions.

In witness whereof I have hereunto set my hand.

WILLIS JOHN PIPPERT.
